Attorney

UNITED STATES PATENT OFFICE.

OSCAR F. MÜLLER, OF DORCHESTER, MASSACHUSETTS, ASSIGNOR TO THORP & MARTIN TYPEWRITER CO., OF BOSTON, MASSACHUSETTS, A CORPORATION OF MASSACHUSETTS.

TYPE-WRITER PLATEN.

1,254,150.

Specification of Letters Patent. Patented Jan. 22, 1918.

Application filed July 7, 1917. Serial No. 179,153.

To all whom it may concern:

Be it known that I, OSCAR F. MÜLLER, heretofore a citizen of Germany, now seeking citizenship in the United States, first 5 papers filed Dec. 31, 1914, petition for second papers filed Feb. 17, 1917, residing at Dorchester, county of Suffolk, Commonwealth of Massachusetts, have invented certain new and useful Improvements in Type- 10 Writer Platens, of which the following is a specification.

This invention relates to platens for typewriters, adding machines and the like, and particularly to a platen of the so-called 15 "noiseless" type, the same being constructed in a manner in which a deadening of the sound of the type shock is effected.

Various efforts have been made with more or less success to accomplish this result in a 20 practical platen adapted for commercial manufacture and actual service use. While some deadening effect has been produced by different devices one of the great difficulties has been to devise a platen which could be 25 produced in quantity and by convenient methods and which would have a maximum degree of "silence" while maintaining a sufficient rigidity of structure.

The problem of securing a rigidity of 30 structure without involving a degree of density which would make for noise has been a difficult one. A great variety of materials have been employed and it has usually been found necessary to employ 35 a dense or rigid structure and then attempt to silence it by packing. The matter of packing has been difficult from a commercial point of view inasmuch as the filling of a pack to secure any degree of uniformity 40 has been difficult and furthermore such pack has had a tendency to sag or settle.

Among packings which have been favored, have been those of fibrous material such as cotton. This has been variously applied 45 either as a stuffing or in the form of fabricated fiber which in some instances has been wound into layers or shells forming strata of the roll.

Throughout these various structures there 50 has been, so far as I am advised, an inherent difficulty in that the material, if stratified, contained one or more strata forming a dense and therefore resonant layer, which acted independently of the deadening layers. If unstratified there was either a lack

of strength or a lack of uniformity or both. In my invention I secure exterior strength and rigidity sufficient to bear the actual type contact surface with a progressive decrease of density so that any vibration set 60 up is led in and progressively absorbed toward the center before it can reach the shaft and thus be transmitted to the rest of the machine. The construction and utility of my invention will be more fully disclosed 65 in the specification which follows. In the drawings I have shown a form of typewriter platen which I have found suitable for practical use and well adapted to manufacture. Throughout the drawings and specification 70 like reference numerals are correspondingly employed and in the drawing:

Figure 1 is a transverse sectional view of a typewriter platen in accordance with my invention.

Fig. 2 is a longitudinal section, and

Fig. 3 is a similar view of a platen also in accordance with my invention, but representing slightly different structure from that indicated in Fig. 1.

Referring to Fig. 1 my roll consists of the usual outer shell 1 of hard rubber within which is a core body 3 of progressively decreasing density from the surface inward toward the center which I have endeavored 85 to graphically indicate by the stippling in Fig. 1.

This core might be a molded integral core treated to produce a decreasing density from the surface inward, but as found in 90 practising my invention, a core may be advantageously made by winding under suitable tension a strip of fabric such as cotton cloth upon a thin inner shell 4 which latter forms the opening for the platen shaft.

The core is then treated to produce a progressively decreasing density from the surface inward. A very simple and inexpensive manner of effecting this treatment is by immersion of the core in a bath of hot 100 paraffin, the time of immersion necessary for penetrating gradually and in a diminishing degree toward the interior of the rolls depending upon the density of the fabric employed and the degree to which the molten 105 paraffin is heated. By limiting the impregnation to the outer layers of the core an elastic cushion is formed by the flexible fabric of the inner layers and the air inclosed by the surrounding impregnated external por- 110

tion. In Figs. 2 and 3 I have indicated at 3¹ by lines of progressively decreasing heaviness inwardly a core formed by thus winding and impregnating. While paraffin is perhaps the cheapest and one of the best materials which can be used, various other waxes or like substances or compounds may be employed. I find that the waxes are particularly effective as they have sound deadening properties and are readily applied hot and when hardened produce considerable external rigidity while even in their attenuated interior penetration they act sufficiently as binders to unify the layers of fabric and produce a sufficient structural strength to make a good carrying core for the exterior shell. I find further in the practice of my invention that a wire shell or cage 2 as shown in Figs. 1 and 2, may be conveniently embodied with the core by placing on said core prior to immersion. This further unifies the structure and adds to the elasticity of the core.

Various modifications may obviously be made in the materials, the degree and extent of impregnation and manner of assembly employed in my invention, all without parting from the spirit thereof, if within the limits of the appended claims.

30 What I therefore claim and desire to secure by Letters Patent is:

1. A platen core of the class described comprising an impregnatable body decreasingly impregnated from the surface inward with a sound-deadening agent.

2. A platen core of the class described comprising a fibrous impregnatable body

decreasingly impregnated from the surface inward with a sound-deadening agent.

3. A platen core of the class described, 40 comprising a body of fabricated fiber wound upon itself and decreasingly impregnated with a wax from the surface inward.

4. A platen of the class described, comprising a body decreasingly impregnated with a wax from the surface inward. 45

5. A platen of the class described, comprising a body of fabricated fiber wound upon itself and impregnated with a wax from the surface inward, a wire shell inclosing said core and included in said impregnation and a type shell lodged thereon. 50

6. A platen core of the class described, comprising a fibrous body decreasingly impregnated from the surface inward with a 55 waxy filler.

7. A type platen core consisting of an impregnatable body decreasingly impregnated with a sound deadening agent.

8. A type platen core consisting of a 60 fibrous body, and decreasingly impregnated with a sound absorptive agent in a liquid state which agent is adapted to be hardened by exposure to atmosphere.

9. A type platen core consisting of a body 65 of stratified material decreasingly impregnated with a sound-deadening agent adapted to unify the strata of the stratified body.

In testimony whereof I affix my signature in presence of two witnesses.

OSCAR F. MÜLLER.
